THE CLASP

Henry Gragg and Donald F. Bell, Prescott, Ariz.,
assignors of one-third to Laurence S. Mason,
Prescott, Ariz.

Application September 20, 1949, Serial No. 116,812

1 Claim. (Cl. 24—49)

1

The invention relates to new and useful improvements in a tie clasp for four-in-hand neckties and more in particular to a tie clasp common on the present day market which has a member for engaging the shirt and a member for holding the tie in place against the shirt. It is common practice to have the part of the clasp which holds the tie in place in the form of a link chain through which the tie may be inserted or to be formed as an integral part of the member which engages the shirt and be adapted to frictionally hold the tie against the same. In either case it is also common practice to mount lodge emblems, ornamental jewelry, figures, or initials of gold and the like, suspended from the link chain or attached directly to the member which frictionally engages the tie as the case may be. Some of these emblems are very valuable, sentimentally and otherwise. The clasps of the type described above are secured to the shirt solely by frictional engagement of the members of the clasp. Such clasps have no positive holding means other than friction and they are often easily dislodged and lost.

An object of the present invention is to provide a clasp of the above type with a locking means which positively grips the shirt and cannot be removed without the wearer releasing the locking means.

A further object of the invention is to provide a tie clasp of the above type having inner and outer members between which the shirt pleat is placed with an arm carrying prongs which are adapted to be imbedded in the shirt fabric and a keeper for holding the arm in closed position.

In the drawings:

Figure 1 is a top view of the tie clasp with the holding arm in closed or locked position;

Figure 2 is a rear plan view of the same;

Figure 3 is a front plan view of the same;

Figure 4 is a section on the line 4—4 of Figure 1;

Figure 5 is a side view of the locking arm, and the supporting means therefor;

Figure 6 is a view of the end of the inner member and showing the lugs for supporting the holding arm; and

Figure 7 is a front plan view, on a smaller scale, showing a modified form of mounting the emblem.

The improved tie clasp includes inner and outer members which are formed preferably from a single piece of wire, shaped and disposed so as to slidably engage the shirt pleat and frictionally grip the same. An arm is pivotally supported by

5 the inner member and is provided with prongs which are adapted to be imbedded in the shirt for holding the clasp on the shirt. The arm is held in closed position by a keeper. A link chain in one form of the invention, is secured to the ends of the outer member of the tie clasp and the tie is placed between said outer member and the link chain for holding the same in position on the wearer. An emblem may be mounted on the chain between the ends thereof, or the emblem may be mounted on the tie holding bar direct.

Referring more in detail to the drawings, and particularly to Figures 1 to 6 thereof, the tie clasp includes an outer member 1, and an inner member 2. The outer member includes two parallel bars 3, 3 which are integrally joined at the outer end as indicated at 4. These bars are parallel and slightly spaced from each other. The inner member of the tie clasp likewise includes two bars 6, 6 formed integral with the bars 3, 3 respectively. The bars 6, 6 at the end of the clasp, where the inner member is joined to the outer member, are close together for a short distance and then the bars widen out as indicated at 7, 7. These bars as indicated at 7, 7 are also bent upwardly into the plane of the bars 3, 3, but lie outside of said bars 3, 3. These bars 6, 6, toward the outer or free end of the inner member are again bent inwardly at 8, 8 and joined at 9. The outer end of the inner member extends downwardly below the bars 3, 3 so as to provide an open mouth to receive the pleat of the shirt. The inner and outer members will spring away from each other and permit the insertion of the fabrics therebetween.

Inasmuch as the inner member is curved upwardly into the plane of the bars 3, 3 when the clasp is in place, the spring of the bars will cause the clasp to frictionally grip the shirt.

40 Depending from the bars 7, 7 are lugs 7^a, 7^a, which are joined by a cross bar 10. This cross bar supports an arm 11 which is mounted thereon so as to swing freely toward and away from the inner member of the tie clasp. The arm carries sharp prongs 13, 13 which are struck up from the arm. The arm is shaped so that when it is swung to closed position as indicated in Figure 1, the prongs will project out through the space between the bars 3, 3 of the outer member and will penetrate the pleat of the shirt.

50 Mounted on the bars 6, 6 of the inner member is a sleeve 14 which is rigidly attached to said bars. This said sleeve carries a keeper 15 which extends downwardly, thence rearwardly and thence upwardly for a short distance so that the

arm can be moved into the keeper and held therein by the upturned portion. The arm 11 extends beyond the keeper 15 and provides a finger grip whereby the arm can be flexed toward the inner member to a position opposite the entrance to the keeper and then moved laterally into the keeper behind the upturned portion and thus positively locked in closed position. The arm terminates short of the outer end of the clasp and will be concealed within the pleat of the shirt.

In the form of the invention shown in Figures 1 to 6, attached to the clasp is a link chain. This chain is indicated at 17. At the free end of said outer member is a lug 18 and one end of the chain is linked thereto. The sleeve 14 has a projecting arm 19 and the other end of the chain is secured thereto. The chain is of such length that the tie will extend between the chain and the clasp and the chain will drape gracefully over and across the tie, holding the tie in position on the wearer.

Mounted on the link chain intermediate the ends thereof may be placed an emblem of a lodge or fraternity, ornamental jewelry, the initials of the wearer or other ornaments. The ornament is indicated at 20 in the drawings.

When it is desired to place the tie clasp on the shirt, the arm is released and swung to open position. The shirt pleat is then entered into the open mouth 16 between the outer and inner members of the tie clasp. As the clasp is pushed onto the shirt, it will be gripped between the inner and outer members which frictionally engage the shirt. When the clasp has been properly placed on the shirt then the arm is swung to closed position and prongs caused to imbed in the fabric of the shirt. The outer or free end of the arm is then placed in the keeper and this will firmly lock the arm in closed position.

The tie is inserted between the clasp and the chain and the chain will support the emblem carried thereby against the background of the tie. These ornaments are often of great value to the wearer. The improved clasp, positively locked to the shirt, removes all worry as to the clasp being dislodged and lost.

In Figure 7 there is shown a modified form of mounting for the emblem. The chain and the lugs to which it is attached are not used. The tie clasp otherwise is the same as described above, that is, the clasp includes the outer member 1, an inner member 2, a latch arm 11 with prongs 13, 13 and a keeper 15. The emblem 20 is mounted on the bars 3, 3 of the outer member 1 and midway between the ends thereof. This is accomplished by soldering or otherwise securing the emblem rigidly to the outer face of the bars 3, 3. In this form of mounting for the emblem the tie

and the pleat of the garment are both passed between the inner and outer member of the clasp so that the outer member carrying the emblem will overlie the tie. After the clasp has been placed, the arm 14 is swung to closed position thus embedding the prongs in the pleat of the garment and the end of the arm is then placed in the keeper 15. This securely locks the clasp to the garment, holds the tie properly positioned and displays the emblem against the background of the tie.

It is obvious that many changes may be made in the details of construction and shaping of the parts without departing from the spirit of the invention as set forth in the appended claim.

We claim:

1. A tie clasp for four-in-hand neckties comprising inner and outer members of flexible material integrally joined at the outer end of the clasp, said members being shaped and disposed relative to each other so as to slidably and frictionally engage a shirt pleat, an arm pivotally supported by the inner member at the inner end portion thereof and extending along said inner member to a point adjacent the outer end of said clasp, fabric gripping means carried by said arm intermediate the ends thereof and adapted to grip the shirt pleat when the arm is in closed position, a rigid keeper supported by said inner member adjacent the outer end of the clasp, said keeper having the end portion thereof offset laterally to overlie the arm and turned back toward said inner member to provide a recess into which the end portion of the arm may be sprung for positively holding the arm in closed position, said arm being dimensioned so as to extend beyond said keeper and provide a finger grip for moving said arm into and out of locking engagement with the keeper, said arm terminating short of the outer end of the clasp and means associated with said clasp for supporting and displaying an emblem.
